DISPLAY STAND

Frank A. Remke, Cincinnati, Ohio

Application April 30, 1948, Serial No. 24,180

4 Claims. (Cl. 211—150)

1

The present invention relates to improvements in merchandise display devices and is particularly directed to a display stand for small, fragile articles such as jewelry or the like.

An object of the invention is to provide a stand for displaying jewelry to the best advantage and which precludes contact between each article displayed thereon and also prevents marring of the surfaces of the articles when the stand is handled for display purposes.

Another object of the invention is to provide a stand having a number of jewelry display plates pivoted thereto and disposed in parallel, vertical spaced relation in offset positions to provide a readily operable and convenient stand for the display of small merchandise.

My invention consists in certain novel combinations and arrangements of parts for attaining the foregoing objects as will be more fully set forth and claimed hereinafter. In the accompanying drawing I have illustrated one example of the embodiment of my invention, wherein:

Fig. 1 is a top plan view of my display stand.

Fig. 2 is a front elevation of the stand shown in Fig. 1.

Fig. 3 is a side elevation of the stand.

Fig. 4 is an enlarged fragmental section taken on line 4—4 of Fig. 1.

Fig. 5 is an enlarged section taken on line 5—5 of Fig. 1.

Fig. 6 is an enlarged section showing a detail of the stand.

The reference numeral 10 generally indicates the display stand frame which has a front wall 11 and a relatively higher rear wall 12 interconnected by side walls 13 and 14. As most clearly illustrated in Figs. 3 and 5 the side walls have top edges 15 and 16 respectively which are inclined upwardly in the direction of the rear wall 12. The stand is preferably made from a transparent synthetic resinous material and has the front wall 11 integrally joined to the side walls 13 and 14 by round corner portions 17 and 18 respectively, the rear edges of the side walls being secured to the ends of the rear wall by synthetic joints. The stand is made rigid by a rectangular plate 19 which is secured at its ends to the interior surfaces of the front and rear walls of the stand by synthetic joints 20.

A number of parallel support bars 21 are positioned between the front wall 11 and the rear wall 12 in vertically spaced relationship and in horizontally offset positions. The bars are grouped together at the center of the frame into two upwardly convergent rows, and as illustrated in

2

Figs. 2 and 4 said bars are also inclined upwardly toward the rear frame wall so that the best light reflection is obtained for the displayed articles and plates carried by each bar may be readily manipulated and the articles thereon easily observed by prospective customers of the merchandise carried by said plates.

A means for pivotally mounting the ends of the bars to the frame is most clearly illustrated in Fig. 5 wherein a pin 22 is embedded in each end of a bar 21 and has its free end extending into a bearing hole 23 formed through the adjacent front or rear wall. A longitudinal slot 24 is formed through the outer edge of each bar for receiving and supporting the inner edge portion of a display plate 25. As illustrated in Fig. 6 a means for securing the plate to the slot comprises an internally threaded screw 26 inserted in aligned bores 27 and 28 formed through the bar and the plate and which cooperates with an exteriorly threaded screw 29 inserted through the opposed end of the aligned bores and cooperating with the internal threaded screw 26. The upper surface of each display plate is covered with a simulated velvet material 30 preferably of a green color and said plates are each provided with a number of holes 31 for receiving pieces of jewelry 32 (Fig. 6).

With reference to Figs. 2 and 4 it will be noted that the two outer portions of the lowermost plates rest upon the inclined top edges 15 and 16 of the side walls 13 and 14 respectively whereby said lowermost plates are supported by the side walls and the respective pivot bars 21. The remaining display plates situated above the lowermost plates each have secured to their outer, under portion a spacer block 33 which maintains said plates in parallel spaced relation with each other and with the said lowermost plate. The blocks may be secured to the plate ends by screws 34 (Fig. 4) which pass through the plates and are internally threaded to the blocks.

It will therefore be noted that I have provided a dependable and simplified display stand which normally maintains a plurality of jewelry display plates in parallel spaced relationship and which is manually operated to cause the plates to be successively turned on their respective pivot mountings for observation of successive pieces of jewelry secured on the plates.

What is claimed is:

1. In a display stand the combination of a front wall, a relatively higher rear wall, a side wall interconnecting the front and rear walls and having an upper edge inclined upwardly in

the direction of the rear wall, a number of parallel bars between the front and rear walls in vertically spaced and horizontally offset positions, said bars being inclined upwardly in the direction of the rear wall, means for pivotally mounting the respective ends of the bars to the said front and rear walls, a display plate secured at its inner end to each bar, the outer portion of the lowermost plate resting upon the top edge of the adjacent side wall, and a spacer block secured to and depending from the outer portion of each of the other display plates with its lower end in engagement with the upper surface of the adjacent plate.

2. A display stand comprising the combination of a front wall, a relatively higher rear wall, side walls interconnecting the front and rear walls and each having an upper edge inclined upwardly in the direction of the rear wall, a number of spaced parallel bars disposed between the front and rear walls in two oppositely inclined rows of vertically spaced bars, said bars being inclined upwardly in the direction of the rear wall, means for pivotally mounting the respective ends of the bars to the said front and rear walls, a display plate secured at its inner end to each bar, the outer portion of the lowermost plates in each row resting upon the top edge of the adjacent side wall, and a spacer block secured to and depending from the outer portion of each of the other display plates in the rows with its lower end in engagement with the upper surface of the adjacent plate.

3. A display stand comprising the combination of a frame having a front and a rear wall, a plurality of pairs of inclined pivot bars supported

by said front and rear walls across the central portion of the frame in parallel spaced relationship, each of said bars having an elongated groove formed therein, display plates each having its inner edge disposed in its respective groove in the bars, means for securing each of said plate edges to its bar, side walls interconnecting the front and rear walls of the frame and each having an inclined plate supporting upper edge disposed parallel to the bars, and spacer blocks interposed between adjacent plates and carried by the uppermost of said adjacent plates.

4. In a display stand the combination of a rectangular frame, a plurality of inclined pivot bars supported by the frame in parallel, proximate relationship centrally of the frame, an elongated groove formed in each bar, display plates each having its inner edge secured in its respective groove in the bars, spacer blocks interposed between the outer free portions of adjacent plates and carried by the uppermost of said adjacent plates, said frame being adapted to support the lowermost plate.
